UNITED STATES PATENT OFFICE

WILLIAM A. STROUD, OF WILKESBORO, NORTH CAROLINA

DESIGN FOR A DRINK MIXER

Application filed August 5, 1932. Serial No. 44,529. Term of patent 14 years.

To all whom it may concern:

Be it known that I, WILLIAM A. STROUD, a citizen of the United States, residing at Wilkesboro, in the county of Wilkes, State of North Carolina, have invented a new, original, and ornamental Design for a Drink Mixer, of which the following is a specification, reference being had to the accompanying drawing, forming a part thereof:

Figure 1 is an isometric view looking at one side of the article, showing my new design; and

I claim:

The ornamental design for a drink mixer, as shown.

WILLIAM A. STROUD.
